UNITED STATES PATENT OFFICE

170,520

RADIO RECEIVER CASING

Louis Boji, Wadena, Iowa, and Paul J. Oslac,
Chicago, Ill., assignors to McGregor Electronic
Industries, Inc., McGregor, Iowa, a corporation
of Delaware

Application January 22, 1953, Serial No. 23,261

Term of patent 3½ years

(Cl. D56—4)

To all whom it may concern:

Be it known that we, Louis Boji and Paul J. Oslac, citizens of the United States, residing at Wadena, Iowa, and Chicago, Illinois, respectively, have invented a new, original and ornamental Design for a Radio Receiver Casing, of which the following is a specification, reference being made to the accompanying drawing, forming a part hereof.

In the drawing:

Fig. 1 is a perspective view of a radio receiver casing embodying our new design;

Fig. 2 is a front elevational view of the same;

Fig. 3 is a side elevational view as seen from

the right hand side in Fig. 2; and
Fig. 4 is a top plan view thereof.

We claim:

The ornamental design for a radio receiver casing, substantially as shown and described.

LOUIS BOJI.
PAUL J. OSLAC.
